CAN-OPENING FUNNEL

Charles F. Bertschinger, Rosedale, N. Y., assignor,
by mesne assignments, of three-fourths to
Tide Water Associated Oil Company, New
York, N. Y., a corporation of Delaware

Application July 17, 1933, Serial No. 680,805

9 Claims. (Cl. 221—23)

The object of this invention is to provide a simple and inexpensive article with which a sealed can may be readily opened and its contents may be directed without spilling into the 5 crank-case of an internal combustion engine, or wherever it may be desired to apply the liquid. A particular object is to defeat substitution. Can opening devices which cut or puncture the ends of cans do not prevent refilling, because cheap 10 apparatus is available with which new ends or heads can be applied to branded can bodies. It is a feature of this invention that the exit opening is cut in the side of the can.

A further object of the invention is to provide 15 an article with which the can is opened by leverage, either the can or the article serving as the lever, the article itself requiring no moving parts.

Another object of the invention is to provide 20 an article which catches liquid that would otherwise drip after a can has been emptied and which delivers this residual liquid with the contents discharged from the next can that is opened.

The article comprises a tube, a knife and a 25 fulcrum, all rigidly connected, the relations being such that the fulcrum is engaged by the rim of the can, after which by relative tilting movement the side of the can is forced over the knife, or the knife is forced into the can. Means are 30 present whereby the can, when opened, is supported in an inclined position over the top of the tube, while its contents pour into and through the tube. A pocket is also provided for retaining liquid that adheres to the interior of the tube and would otherwise drip when the article is set aside after use, this pocket being arranged to 35 receive such liquid when the article is disposed with the lower end of the tube higher than the upper end.

In the accompanying drawings, forming part 40 hereof:

Fig. 1 is a side elevation of the article, showing a can in position to be opened;

Fig. 2 is a similar view, but in vertical section and showing the can, in dotted lines, in the relative position which it occupies when the can is 45 opened;

Fig. 3 is a front elevation of the article;

Fig. 4 is a side elevation of the article in the position in which it is suspended when not in 50 use, a portion being broken away and sectioned to show liquid retained in the drip pocket;

Fig. 5 is a top plan view of the article; and

Fig. 6 is a perspective view of a can, showing the opening cut in its side immediately adjacent 55 one end.

The body of the article consists of a tube 2, which is preferably larger at the top than at the bottom, after the manner of a funnel, though that is not necessarily essential. A knife 3 projects upward, and somewhat forward, from the top of the tube or funnel, this knife being preferably disposed within but toward the front of the funnel and having a shank 4 which is fixed to the front wall of the tube by screws 5, which permit the knife to be removed. The knife has a forwardly directed puncturing point 6, from which cutting edges 7 diverge and then extend downward along the side edges of the knife.

On the front of the knife, just above the front of the top of the funnel, there is a hooked lug 8, so formed and positioned that the rim 9 of a can 10 may be engaged with it as shown in Fig. 1. This lug constitutes a fulcrum, on which the can may be tilted rearward with sufficient force to cause the knife to penetrate and cut the side wall of the can. The resulting broad opening 11 extends to the end wall or head 12 of the can, so that no liquid is trapped in the can. The tongue 13 cut from the side of the can folds against the inside of the can end.

The top of the funnel is inclined, that is to say the back is higher than the front, so that when the can is forced as far as it is permitted, it is supported in the inclined position shown in Fig. 2, with its side containing the opening 11 sloping downward and forward, in consequence of which all liquid in the can is discharged through the opening into the funnel. For better support of the can in this position, a troughed rest 14 is united or formed with the top of the funnel, extending upward and rearward. A further feature of the device is that it enables the user to control the speed of flow of liquid from the can by varying the angle between the can and the knife, after the opening has been cut in the can and the contents are discharging. Thus, if more rapid emptying is desired, the can may be moved on the fulcrum to a steeper inclination than that shown in Fig. 2, thus hastening the outflow of the liquid, or of the latter portion of the contents.

On the front of the funnel there is a hanging ring 15, so positioned with respect to the center of gravity of the article that, when the article is hung up by this ring, as shown in Fig. 4, the lower end of the tube or funnel is higher than the upper end. To catch the oil or other liquid which clings to the inside of the tube and which would otherwise give an objectionable drip, a pocket 16 is provided in the rear upper portion 50 55 55

of the article. This pocket is preferably formed between the back portion of the funnel and an overhanging wall 17 united or formed with the rest 14, but the precise construction may be varied. When the article is used with another can, the small amount of liquid that was held in this pocket flows out through the tube with the contents of the can.

As the operation of opening the can has been described and is illustrated, the funnel is held vertical and the can is tilted. This is the manner in which the operation is performed if the tube is in or over the breather opening of a crank-case, or the opening of any receptacle into which the contents of the can are to be introduced. If that operation should not be convenient, the can may be opened, by moving either the can or the can-opening funnel from the relative positions of Fig. 1 to the relative positions of Fig. 2, while they are so disposed in space that in the condition shown in Fig. 2 the can will be horizontal, with the opening cut in its upper side. The can and funnel may then be carried in this position, without spilling the contents, to the crank-case, where the can and funnel may be inverted and the end of the funnel inserted in the breather opening.

It will be evident that the opening of a can and the delivery of its contents into a receptacle are quickly and easily accomplished, and that the article is one that can be manufactured at low cost. The fact that the opening is made in the side of the can makes fraudulent re-filling of the can impossible. For this reason the article is particularly useful in connection with the sale of branded oil or other commodity from a sealed can. Another advantage of the invention is that the same article will open and receive the contents of cans of widely varying sizes.

40 I claim:

1. An article for opening a can and directing its contents, comprising a tube, a knife rigidly secured to the tube and projecting from the receiving end thereof and adapted to cut an opening in the side of the can at one end, a fulcrum rigidly fixed adjacent and in front of the knife and adapted to be engaged by the rim of the can, and means at the receiving end of the tube for supporting the can at an inclination relative to the tube when the opening has been cut as the result of relative tilting movement between the can and the article.

2. An article for opening a can and directing its contents, comprising a tube, a knife rigidly secured to the tube and projecting from the receiving end thereof and adapted to cut an opening in the side of the can at one end, a fulcrum rigidly fixed adjacent and in front of the knife and adapted to be engaged by the rim of the can, and means forming a pocket to retain liquid that would otherwise drip, when the article is disposed with the lower end of the tube higher than the upper end.

3. An article for opening a can and directing its contents, comprising a tube, a knife rigidly secured to the tube and projecting from the receiving end thereof and adapted to cut an open-

ing in the side of the can at one end, a fulcrum rigidly fixed adjacent and in front of the knife and adapted to be engaged by the rim of the can, means forming a pocket to retain liquid that would otherwise drip, when the article is disposed with the lower end of the tube higher than the upper end, and means on the article for suspending it in such position when not in use.

4. An article for opening a can and directing its contents, comprising a tube, a knife rigidly secured to the tube and projecting from the receiving end thereof and adapted to cut an opening in the side of the can at one end, a fulcrum rigidly fixed adjacent and in front of the knife and adapted to be engaged by the rim of the can, means at the top of the tube for supporting the can at an inclination relative to the tube when the opening has been cut as the result of relative tilting movement between the can and the article, and means forming a pocket to retain liquid that would otherwise drip, when the article is disposed in such position that liquid clinging to the inside of the tube drains backward in the tube away from the discharge end.

5. A can-opening spout or funnel article, comprising a tube, a knife and a fulcrum, all rigidly connected as a unit, said fulcrum being adapted to be engaged by the rim of a can and the relations being such that by relative tilting movement between the can and the unit an opening is cut in the can.

6. A can-opening spout or funnel article, comprising a tube, a knife and a fulcrum, all rigidly connected as a unit, said fulcrum being adapted to be engaged by the rim of a can and the relations being such that by relative tilting movement between the can and the unit an opening is cut in the can, the top of the article having a support for the opened can disposed at an inclination to the tube.

7. A combination can-opener and spout, comprising a tube, a knife attached to said tube and projecting at the top thereof for cutting the side of a can, said knife being a blade having a puncturing point and lateral cutting edges and adapted to cut an opening in the side of the can and to fold a resulting tongue inward toward the head of the can, and a fulcrum firmly supported adjacent the knife and adapted to be engaged by the rim of the can.

8. A combination can-opener and spout comprising a tube, a knife projecting at the top of the tube, and a fulcrum adjacent said knife, said knife and fulcrum being firmly supported by the tube in such relation that the rim of a can may be engaged with said fulcrum and the side of the can may be forced over the knife by using the can as a lever.

9. In a combination can-opener and spout, a tube open at both ends, a knife attached to the tube at the top thereof for puncturing the side of a can, and a fulcrum fixed adjacent said knife and adapted to be engaged by the rim of the can, the speed of flow of liquid from the can being controlled by varying the angle of the can with respect to the knife.

CHARLES F. BERTSCHINGER.
